(57) CLAIM

The ornamental design for a lighting fixture as shown and described.

DESCRIPTION

FIG. 1 is a front right perspective view from below of a lighting fixture according to the new design;
FIG. 2 is an enlarged front elevational view thereof;
FIG. 3 is an enlarged right side elevational view thereof;
FIG. 4 is an enlarged left side elevational view thereof;
FIG. 5 is an enlarged rear elevational view thereof;
FIG. 6 is an enlarged top view thereof;
FIG. 7 is an enlarged bottom view thereof;
FIG. 8 is an enlarged view of detail 8 in FIG. 1;
FIG. 9 is an enlarged view of detail 9 in FIG. 2; and,
FIG. 10 is an enlarged view of detail 10 in FIG. 4.
The broken lines in the drawings illustrate portions of the lighting fixture that form no part of the claimed design.
The lighting fixture is shown with a symbolic break in its width. The appearance of any portion of the design between the break lines forms no part of the claimed design.
The double dash lines shown in FIGS. 1, 2, 4, and 8-10 depict the boundaries of the enlargements that form no part of the claimed design.
